UNITED STATES PATENT OFFICE.

JOHN A. SECOR, OF LAPORTE, INDIANA, ASSIGNOR TO M. RUMELY COMPANY, OF LAPORTE, INDIANA, A CORPORATION OF INDIANA.

CARBURETER.

1,105,003.

Specification of Letters Patent. Patented July 28, 1914.

Application filed September 7, 1911. Serial No. 648,022.

To all whom it may concern:

Be it known that I, JOHN A. SECOR, a citizen of the United States, residing at Laporte, in the county of Laporte and State 5 of Indiana, have invented a certain new and useful Improvement in Carbureters, of which the following is a specification.

My invention relates to improvements in carbureters and is illustrated diagrammatically in one form in the accompanying drawing wherein is shown a transverse section through the device.

Like parts are indicated by like letters in the drawing.

15 The carbureting or vacuum chamber A has at one end the air intake port A¹ and at the other end the mixture discharge port A² controlled respectively by the similar air intake and mixture discharge valves A³ A⁴, 20 a description of one of which will suffice for both.

The valve chamber B contains the cylindrical drum B¹ opening at one side into the carbureting chamber and having perforate 25 top and bottom walls B². A valve stem B³ is slidably mounted in a sleeve B⁴ in the lower wall of the valve chamber and in a boss B⁵ in the upper wall thereof, and carries the two puppet valves B⁶ in opposition 30 one to the upper and one to the lower wall of the drum and concentric with the perforations in said walls and so arranged as to form balanced puppet valves.

A bracket C, slidably and adjustably 35 mounted upon the wall of the chamber A is held in position by the cap screw C¹ and supports the pivotally mounted block C² slidably mounted upon the lever C³ and adjustably held in position therein by the set screw C⁷. The counter balance C⁸ is slidably mounted upon the lever C³ on the side 40 opposed from the block C² and held adjustably in position by the set screw C⁹. Liquid fuel and water are supplied to the carbureting chamber by means of the conical fuel nozzles D fed from the reservoirs D¹ and controlled by the thumb screws D², 45 operating needle valves not shown.

It is evident that while I have shown in 50 my drawing an operative device, still many changes might be made both in size, shape and arrangement of parts without departing materially from the spirit of my invention. Parts might be made or additional parts 55 added or some of the parts modified in posi-

tion or shape without departing in any way from the spirit of my invention. I wish, therefore, that my drawing be regarded as in a sense diagrammatic.

The use and operation of my invention 60 are as follows: Water and fuel are supplied to the vacuum chamber through the supply nozzles, the opening of each of said nozzles being adjusted in the usual manner by means of the needle valve to make them responsive in their feed to that degree of vacuum in the carbureting chamber which will furnish at all times a suitable mixture for the engine. The mixture is drawn from the carbureter into the engine in the usual 65 manner and needs no further illustration. In order that the vacuum in the carbureting chamber may be controlled and adjusted responsive to the condition of the engine, thereby giving a suitable mixture for all 70 power, speed and load, means must be employed for controlling simultaneously though differentially both air intake and mixture discharge ports. These means in my present invention take the form of balanced puppet valves which are given a differential movement by appropriately proportioning the relative lengths of the lever arms controlling each of said valves. It will be observed that the bracket on the carbureter may be moved, thus varying the position of the fulcrum of the controlling 75 lever, and that when this is done some point 80 will be reached at which any position of the lever responds to any certain condition 85 in the engine and will so affect the air intake and mixture discharge valves that a suitable vacuum will be had in the vacuum chamber to produce a suitable mixture. It will, of course, be obvious that some system 90 of valves other than those which I have indicated might be used. I have here preferred, however, to use a plurality of puppet valves controlling both the air intake and mixture discharge ports. These puppet 95 valves are so positioned that they are what is known as balanced valves and they operate therefore quite independent of and not affected by any change in the vacuum or 100 pressure or any change in the velocity of the gases passing by them. I have provided also a counterbalance weight which may be so adjusted in position as to counterbalance the weight of the connecting rod and the 105 weight of the lever. The result, therefore, 110

is that I provide a completely balanced system in which the only load carried or moved by the governor is the friction load, and in which the governor may be made peculiarly sensitive in view of the fact that there is practically no resistance to or drag upon its operation, due either to any variations in the velocity or absolute pressure of the gas or to the force of gravity acting upon the moving parts. Of course, other devices of valves and other balancing systems might be used wherein the system would still be balanced in every respect and wherein the variation in the operation of the carbureter or the engine would in no wise vary the load on the governor. At the same time, however, I have deemed it expedient for the purpose of this invention to illustrate it as applied to puppet valves connected by an adjustable controlling lever.

I claim:

1. A carbureter having a fuel inlet and air intake and mixture discharge ports, and balanced valves controlling said ports, the effective areas of valve opening being directly proportional to the movement of the valve, and means for operating said valves simultaneously but unequally, and a balancing device associated with said valve operating means, whereby the two sides of such movable valve system are at all times in mechanical balance.

2. A carbureter having fuel inlet and air intake and mixture discharge ports, and balanced piston valves controlling said ports, the effective areas of valve opening

being directly proportional to the movement of the valve, and means for operating said valves simultaneously but unequally, and a balancing device associated with said valve operating means, whereby the two sides of such movable valve system are at all times in mechanical balance. 49

3. A carbureter, having a vacuum chamber having fuel and water inlets each having a nozzle opening into the carbureter chamber separate and distinct one from the other and adapted to vary but unequally their feeds responsive to variations in the vacuum in the carbureter chamber, air intake and mixture discharge ports and balanced piston valves controlling said ports, and means for operating said valves simultaneously but unequally. 50

4. A carbureter, having a vacuum chamber having fuel and water inlets each having a nozzle opening into the carbureter chamber separate and distinct one from the other and adapted to vary but unequally their feeds responsive to variations in the vacuum in the carbureter chamber, air intake and mixture discharge ports and balanced piston valves controlling said ports, and means for operating said valves simultaneously but unequally, and adjustable connections between the two valves whereby their relation can be varied at will. 55
